[57] CLAIM

The ornamental design for an earring organizer, as shown.

DESCRIPTION

FIG. 1 is a front elevational view of an earring organizer showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and

FIG. 7 is a front left perspective view thereof.

The broken line showing of a pair of earrings in FIG. 7 is for illustrative purposes only and forms no part of the claimed design.

FIG. 4
